UNITED STATES PATENT OFFICE.

LORENZ R. WOLFF, OF LOS ANGELES, CALIFORNIA.

AUTOMATIC STOP AND START DEVICE FOR PHONOGRAHS.

1,407,908.

Specification of Letters Patent. Patented Feb. 28, 1922.

Original application filed April 19, 1919, Serial No. 291,380. Divided and this application filed April 6, 1920. Serial No. 371,757.

To all whom it may concern:

Be it known that I, LORENZ R. WOLFF, a citizen of the United States, residing at Los Angeles, in the county of Los Angeles and State of California, have invented a new and useful Automatic Stop and Start Device for Phonographs, of which the following is a specification.

My invention relates to the class of machines used for the purpose of reproducing sound from records, the invention as hereinafter shown and described more particularly relating to the control of a phonograph of the type used for reproduction of sound from disk records.

This application is a divisional application covering certain subject matter disclosed in my co-pending application for patent filed on the 19th day of April, 1919, Serial No. 291,380, for a phonograph.

The principal object of my invention is to produce a device to be used in connection with a disk record machine, such device embodying an automatic starting and stopping mechanism which also includes a switch for controlling the electric current used for operating the motor power which drives a phonograph.

Other objects and advantages will appear hereinafter from the following specification.

Referring to the drawings, which are for illustrative purposes only,

Fig. 1 is a plan view of a device embodying a form of my invention.

Fig. 2 is a side elevation, partly in section, of the device shown in Fig. 1.

Fig. 3 is an enlarged plan view, partly in section, of the tone arm supporting device and switch mechanism.

Fig. 4 is a vertical sectional view on line 4-4, Fig. 3.

Fig. 5 is a side elevation of that portion of the machine shown in Fig. 3, and in addition thereto the tone arm and the parts carried therewith.

Fig. 6 is an enlarged rear elevation, partly in section, of the tone arm member of the switch.

Fig. 7 is a view similar to Fig. 6 showing the parts in resetting position.

Fig. 8 is an enlarged vertical, sectional view on line 8-8, Fig. 3 with the tone arm support omitted.

Fig. 9 is a diagrammatic view showing

the driving mechanism and electrical connections to the automatic starting and stopping device.

20 designates the top of a cabinet which in the form shown constitutes a supporting member for the machine, such supporting member having, secured thereto on the under side, by means of suitable screws 21, a bracket 22 in which is mounted a vertical shaft 23 freely rotatable in the bracket and having its lower end resting upon a ball 24 so that the shaft 23 may rotate with as little friction as possible in the bracket. The shaft 23 extends through an opening 25 formed in the supporting member 20 and has secured thereto by means of a pin 26 a circular table 27, the edge of which is grooved as indicated at 28 to receive a driving cable or cord 29. The shaft 23 extends above the table 27 and forms a centering device for the disk record 30 which rests upon the table.

The cable 29 passes around a grooved pulley 32 which is secured to a shaft 33 mounted in a bracket 34 secured to the under side of the supporting member 20. 36 designates a grooved pulley mounted on the shaft 33, which pulley 36 is driven by means of a cable 37 from a pulley 38 mounted upon a countershaft 39. The shaft 39 is driven through the medium of a large pulley 40 which in turn is driven by a cable 41 from a pulley 42, shown diagrammatically in Fig. 9, mounted on a shaft 43, such shaft 43 being driven by a pulley 49 mounted thereon which in turn is driven by 90 a cable 45 from a pulley 46 on a motor 47 which is mounted in any suitable manner in the phonograph.

The tone arm 50 may consist of any well known design as may also the reproducer 51 mounted on the end of the arm 50, it being understood, however, that the tone arm 50 swings horizontally as is commonly done and that the arm 50 is connected to a horn in the usual manner. The tone arm, however, is not permitted to rest its weight upon the record as is usually done, but is elastically supported by means of an elastic truss construction mounted upon the vertical post 52 of the tone arm. This truss construction consists of a split band 53 secured to the post 52 by means of a bolt 54 and a butterfly nut 55. The split band 53 is provided with a lug

56 to which is secured in any suitable manner a flat spring 57, the outer end of which extends under and supports the head 58 of a square connecting bar 59. 5 60, 60 designate two spring wires which have one end secured in any suitable manner in the lug 56 and their outer ends secured to the head 58 of the bar 59. 61 designates a bridge or support mounted on the wires 60 10 and resting upon the spring 57 to retain the wires 60 and spring 57 in the proper relation to each other. The square bar 59 is provided with a head 62 formed on the outer end thereof in which head 62 is supported two 15 spring wires 63, the outer end of such wires 63 extending into a yoke 64, which yoke 64 is lined with felt or similar material indicated at 65 forming a rest or support which engages the under side of the tone arm near 20 its outer end thereby forming an elastic cushion for the tone arm.

25 Means are provided for running the mechanism according to the length of records played and consists in general of an electric switch by means of which an electric current is controlled for running the motor 47.

30 Mounted on the under side of the supporting member 20 are two binding posts 70 and 71, a wire 72 being connected to the post 70 35 and a wire 73 being connected to the post 71. 74 designates a spring contact member mounted on the post 70 and 75 designates a spring contact member mounted on the post 71. Resting upon the contact member 74 is a rod 76, the upper end of such rod being secured to the lower member 77 of a switch member. The switch member comprises a lower plate 77 and an upper plate 78 connected by means of a central post 79 and a 40 post 80 at each end, such posts being freely 45 slidable in guides 81 formed on a segmental carrier plate 82 which is slidably mounted in a circular path upon a base plate 83, such base plate 83 being secured to the supporting member 20 by suitable screws. The carrier plate 82 is provided with slots 84 through 50 which extend headed pins 85 for the purpose of guiding the carrier plate 82 on the plate 83. The plate 82 is movable in the path of a circle, having its center of movement in the center of the tone arm standard and the switch member is elastically held in elevated position by means of coiled springs 86 on the posts 80.

55 The position of the plate 82 on the base plate 83, and consequently the switch member carried therewith, is regulated by means of the bell crank lever 90 pivotally mounted upon a pin 91 to the under side of the supporting member 20. The end 92 of the arm 90 is provided with a fork 93 which engages the post 76, and the other end 94 of the arm 90 is bent upwardly as indicated at 95 extending through a slot 96 in the supporting member 20 and then outwardly, forming a

pointer 97 which moves over a gage 98 having markings 99 thereon corresponding to the grooves in the record.

60 Mounted upon the square bar 59 of the tone arm supporting mechanism is an arm 100, being held in adjusted position thereon by means of a set screw 101. Vertically slideable in the outer end of the arm 100 is a rod 102 secured to the arm by means of a set screw 103. The rod 102 at its lower end is 75 provided with an extension 104 upon which is secured a pin 105. Pivotaly mounted upon a bolt 106 on the lower end of the rod 102 is a dog 107, such dog having an arm 108 formed thereon which is provided with a notch 109 which receives the pin 105. Mounted on the arm 100 is a flat spring 110 which is engaged by the arm 108 of the dog as hereinafter described. The wires 72 and 73 form a motor circuit in which is arranged electrogenerative mechanism, in the present instance being indicated as a battery 112, it being understood, however, that any common form of connection may be used to a lamp socket. The wires 72 and 73 are connected 90 to the motor 47 which motor drives the table 27 through the connections heretofore described.

95 The phonograph is operated in the following manner:

When the record is selected it is placed upon the table 27 and the pointer 97 is moved to set the mechanism so that the mechanism will stop when the record has finished playing. This is done by preferably having the record marked corresponding to the scale 98. The setting of the pointer 97 moves the post 76 thereby moving the plate 82 and the switch member carried thereby upon the base plate 105 83. The tone arm is then moved down 95 so that the needle 120 engages the face of the record. This downward movement of the tone arm causes the dog 107 to engage the top plate 78 of the switch member and the weight of the tone arm transferred to the switch member pushes the switch member downwardly together with the post 76 thereby bringing the contact member 74 into contact with the contact member 75, 115 closing the electric circuit and starting the motor 47, the motor 47 driving the table 27 through the cable connections heretofore described.

120 During the playing operation the dog being carried on the elastic truss and such mechanism being moved by the tone arm, the dog moves over the plate 78, and at the end of the record passes off the opposite end of the plate 78 thereby permitting the switch member to move upwardly due to the action of the springs 86, which permits the contact member 74 to break contact with the member 75 thereby breaking the electric circuit and stopping the motor.

To return the tone arm out of the way the reproducing mechanism 51 is moved as is commonly done to bring the needle out of contact with the record, and the tone arm 5 is swung back to its original position. As the tone arm is swung back, the dog strikes the end of the plate over which it has just passed, and as the dog is free to rotate on its pivot against the pressure of the end of 10 the plate, the dog is swung into the position shown in Fig. 7 until it has passed beyond the plate 78 when the spring 110, acting against the arm 108 on the dog, pushes the dog into its original position as shown in 15 Fig. 6.

It is to be noted that the plate 78 has an off-set portion 125 which is provided for the purpose of accommodating records which may have the grooves in such position that 20 they are not accommodated by the main portion of the plate 78, and when such off-set portion 125 is used, it is understood that the arm 100 is moved on the square rod 59 to bring the dog 107 into contact with the off-set portion 125 instead of the main plate 78.

While I have shown and described a particular style of table and connections between the phonograph table and the motor, it is to be understood that such driving connections do not form a part of my invention, but that any form of driving connections 30 between the table and the motor may be used without departing from the spirit of my invention.

From the above it will be readily understood that the simple act of moving the tone arm so that the needle will register and contact with the first groove of the record closes the electric circuit and starts the 40 phonograph.

What I claim is:—

1. In a phonograph the combination of a rotatable table for disk records, a motor, a motor circuit, contact members in said circuit for making and breaking the circuit, a switch member mounted on the phonograph, means on the switch member adapted to engage one of said contact members, a plate on said switch member, an elastic supporting member for the tone arm of the phonograph, and means on said elastic supporting member arranged to engage the plate on the switch member.

2. In a phonograph the combination of a rotatable table for disk records, a motor, a motor circuit, contact members in said circuit for making and breaking the circuit, a switch member mounted on the phonograph, means on the switch member adapted 55 to engage one of said contact members, a plate on said switch member, and means on the tone arm of the phonograph arranged to engage said plate to operate the switch.

3. In a phonograph the combination of a 60 rotatable table for disk records, a motor, a

motor circuit, contact members in said circuit for making and breaking the circuit, a switch member mounted on the phonograph, means on the switch member adapted to engage one of said contact members, 70 means on the tone arm of the phonograph arranged to operate said switch to close the contacts, and means for varying the position of the switch with relation to the tone arm.

4. In a phonograph the combination of a rotatable table for disk records, a motor, a motor circuit, contact members in said circuit for making and breaking the circuit, a switch member mounted on the phonograph, means on the switch member adapted 75 to engage one of said contact members, a plate on said switch member, an elastic supporting member for the tone arm of the phonograph, means on said elastic supporting member arranged to engage the plate 80 on the switch member, and means for varying the position of said plate with relation to said tone arm.

5. In a phonograph, the combination of a rotatable table for disk records, a motor, a motor circuit, contact members in said circuit for making and breaking the circuit, a switch member mounted on the phonograph consisting of a plate and a rod carried by 90 said plate arranged to engage one of the contact members, means for elastically holding said plate in elevated position, means on the tone arm arranged to engage said plate to depress said plate whereby said rod 95 closes said circuit through the contact members, and means for varying the position of said plate with relation to the tone arm according to the length of the record to be played.

6. In a phonograph, the combination of a rotatable table for disk records, a motor, a motor circuit, contact members in said circuit for making and breaking the circuit, a switch member mounted on the phonograph consisting of a plate and a rod carried by 105 said plate arranged to engage one of the contact members, means for elastically holding said plate in elevated position, means on the tone arm arranged to engage said plate to depress said plate whereby said rod closes said 110 circuit through the contact members, a lever mounted on the phonograph, a fork on the lever arranged to engage the rod, a pointer on the lever, and a scale on the phonograph coincident with the pointer corresponding 115 to the grooves in the phonograph records.

7. In a phonograph, the combination of a rotatable table for disk records, driving mechanism for the table, controlling mechanism for the driving mechanism, an elastically supported movable plate for operating said controlling mechanism, and depressing means on the tone arm of the phonograph arranged to travel over said plate.

8. In a phonograph, the combination of a 120

rotatable table for disk records, driving mechanism for the table, controlling mechanism for the driving mechanism, an elastically supported plate for operating said controlling mechanism, plate depressing means on the tone arm of the phonograph arranged to travel over said plate, and means for varying the position of the plate with relation to the engaging means on the tone arm.

In testimony whereof, I have hereunto set my hand at Los Angeles, California, this 30th day of March, 1920.

LORENZ R. WOLFF.
